UNITED STATES PATENT OFFICE.

WILLIAM L. CALDWELL, OF CANTON, OHIO, ASSIGNOR, BY MESNE ASSIGNMENTS, TO
UNITED ALLOY STEEL CORPORATION, OF CANTON, OHIO, A CORPORATION OF NEW
YORK.

METALLIC FLUME.

Application filed November 17, 1919. Serial No. 338,695.

To all whom it may concern:

Be it known that I, WILLIAM L. CALDWELL, a citizen of the United States, residing at Canton, in the county of Stark and State of Ohio, have invented a new and useful Metallic Flume, of which the following is a specification.

The invention relates to improvements in metallic flumes in which a thin metal trough is used for conveying water for irrigation, power or similar purposes; the metal trough being formed of successive sections of proper curvature and joined together to form a continuous channel. To facilitate erection of flumes of this character, the joints between the several sections should be made without rivets or bolts, and to allow for expansion and contraction of the metal they should have a certain flexibility; that is, the sections should be permitted to move longitudinally with respect to each other, whereby the possibility of buckling as a result of such expansion and contraction is obviated. The joints should further add a certain amount of circumferential stiffness to the thin shell of the flume sections and should also be made water-tight without the use of solder or the like.

The objects of the invention are to provide a flume with a water-tight joint without the use of rivets, bolts or solder; to provide a joint between the flume sections in which no outer-clamping bar is used; to provide means for allowing for expansion and contraction of the flume without causing buckling; to provide a joint between the flume sections having interior means for forcing the parts into position thus aiding materially in assembling the flume and preventing displacement of the parts by strains placed thereon; to provide means for circumferentially stiffening the structure; and to generally improve and simplify the construction of sheet metal flumes.

The above objects are attained by providing a sheet metal flume made up of semi-circular sections, each section being provided at one end with an external stiffening flange, the plain end of the adjacent section being placed within the flanged end of each section and held in engagement therewith by means of a curved pressure bar and by providing a structural iron hanger which is clamped upon the flanged end of the flume section and provided with means for forc-

ing the curved pressure bar into tight engagement with the plain end of the adjacent flume section.

The invention thus set forth in general terms is illustrated in the accompanying drawings forming part hereof, in which—

Figure 1 is a perspective view of portions of two sections of flume showing the joint.

Fig. 2 is a plan view of portions of two sections of flume at the joint. 65

Fig. 3 is a transverse sectional view through the flume.

Fig. 4 is a fragmentary view of portions of adjoining sections of the flume showing the means for clamping the hanger thereto. 70

Fig. 5 is a fragmentary longitudinal sectional view through a portion of the hanger showing the locking tongue which engages the curved clamping bar.

Fig. 6 is an enlarged sectional view 75 through a portion of the flume, at a joint illustrating the function of the locking tongue.

A practical embodiment of the invention is disclosed in the accompanying drawings, 80 forming a part of this specification in which similar numerals of reference indicate corresponding parts throughout the several views.

In the practical use of flumes, especially for irrigation, it is frequently necessary to 85 construct the flume of considerable length and to support the several sections going to make up the complete flume above the ground; if for instance, it is desired to conduct water across valleys or depressions 90 and at the same time maintain the proper level or inclination so that water may if necessary be carried over intervening elevations.

In order to accomplish this purpose it is 95 frequently necessary to construct trestle-work or other frame-work of considerable height at some points along the length of the flume, while at other points such trestle or frame-work may be comparatively 100 low, the flume being supported throughout its entire length by suitable transverse hangers 1 which are supported at their ends by the trestle or frame-work.

The flume sections which are preferably 105 formed of sheet metal, and as illustrated in the drawings are semi-circular in cross section, are indicated by the numeral 2, these sections being of suitable length to permit of their being easily handled and 110

erected. Each of the sections is plain at one end as shown at 3 and provided at its other end with an outwardly disposed circumferential stiffening flange 4, which 5 obviates the necessity of using an outer clamping bar, the plain end of each section being extended into the flanged end of the adjacent section and overlapped a short distance, as best shown in Fig. 1 of 10 the drawings, when the sections are assembled to form the completed flume.

As illustrated in the drawings the flume sections are preferably formed without corrugations in order that the bottom of 15 the trough or the surface upon which the water flows is smooth, thereby offering the least resistance to the flow of water. In assembling the sections the flanged end of each section should be located toward the 20 point from which the water supply is received in order to offer the least resistance to the flow of the water; thus in Fig. 1, the structure illustrated is designed to permit the water to flow in the direction of the 25 arrow.

The curved pressure bar 5 is arranged to be placed within the overlapped plain end of each section and is of a size and shape to correspond substantially with the curvature of the interior of the flume sections 30 into which the bar is to be seated. These pressure bars are preferably formed with a rounded inner face as shown at 6 in order to present less resistance to the flow of 35 water through the flume, and their ends extend upward slightly above the edges of the flume sections so as to abut the hanger, and prevent the edges of the flume sections from contracting therewith.

40 The hanger 1 is preferably formed of channel iron as illustrated in the drawings and the flume sections are carried therefrom by means of the clamping bolts 7, which are riveted or otherwise connected at their 45 lower ends to the stiffening flange 4 of each flume section. These clamping bolts extend through suitable apertures in the hanger, and nuts 8 are provided thereon for drawing the flume sections toward the hanger, and against the curved pressure bar.

50 The hanger is provided with means acting against the ends of the pressure bar and forcing them directly outward against the side or edge portions of the overlapped 55 ends of the flume sections.

Preferred means for the purpose are the 60 flexible locking lugs 9 which may be tongues stamped and deflected at an acute angle from the web plate of the hanger, whence 65 they extend downward and outward so that their ends will stand fully inside of the pressure bar when the parts are assembled, as shown by full lines in Fig. 5.

65 After assembling the parts thus described in detail, the nuts 8 are first tightened on

the clamping bolts so as to draw the overlapped ends of the flume sections snugly against the pressure bar with the ends thereof in abutment with the underside of the hanger. The locking lugs are then driven 70 upward, by means of a hammer or other suitable tool, until their free ends wedge against the inner side of the pressure bar near the ends thereof; and force them directly outward against the side portions of 75 the overlapped ends of the flume sections.

The bolts are then further tightened so as to clamp the innerlapped end of the one flume section between the overlapped end of the other flume section and the pressure 80 bar, such clamping action being accomplished by the strength of the circumferential flange 4 operating against the curved pressure bar as an abutment.

There is no clamping action of the bolts 85 at the sides of the flume adjacent to the hanger, because the pull of the bolts is substantially parallel with the end portion of the pressure bar; but the action of the locking lugs positively presses the ends of the 90 pressure bar outward so as to clamp the edge portions of the overlapped ends of the flume sections between the end portions of the pressure bar and the abutment formed by the end portions of the circumferential 95 flanges; which are stopped against lateral movement by the clamping bolts.

Thus the overlapped ends of the flume sections are clamped together at the sides as well as at the bottom of the flume; and it is 100 evident that when the tongues 9 have been driven upward to effect the clamping action thus described, they will be locked in such position by their wedging action against the pressure bars as well as by a biting into 105 the same.

For the purpose of further assuring a water tight joint between the sections of the flume a mastic may be applied to the joints between the sections. This mastic may be 110 what is known to the trade as "Gilonite," and when placed in the joints of the flume sections forms a water tight seal between the sections obviating any leakage of the 115 flow of water through the flume at the joints.

Reference is made to my copending applications, Serial No. 338,696, Serial No. 338,697 and Serial No. 338,698, which contain claims to subject-matter which is related to that which is set forth in the claims made 120 in this application, as follows.

I claim:

1. A metallic flume including adjoining sections having overlapping ends, external integral stiffening and clamping means on 125 the outerlapped end, and a pressure bar inside the innerlapped ends, and means at the ends of the external stiffening means for clamping the innerlapped end between the stiffened end and the pressure bar.

2. A metallic flume including adjoining sections having plain ends overlapped, an external flange on the outerlapped end, a pressure bar inside the innerlapped end, and means at the ends of the flange for clamping the innerlapped end between the flanged end and the pressure bar. 5
3. A metallic flume including adjacent sections having plain ends overlapped, an external flange on the outerlapped end, a transverse hanger adjacent to the edges of the overlapped ends, a pressure bar inside the innerlapped end abutting the hanger, and means for clamping the innerlapped 10 end between the outerlapped end and the pressure bar. 15
4. A metallic flume including adjoining sections having overlapped ends, a transverse hanger adjacent to the edges of the overlapped ends, external integral stiffening and clamping means on the outerlapped end and means on the ends of the external stiffening means for drawing the same toward the hanger for clamping the outerlapped 20 end against the innerlapped end. 25
5. A metallic flume including adjoining sections having plain ends overlapped, an external flange on the outerlapped end, a transverse hanger adjacent to the edges of the overlapped end, a pressure bar inside the innerlapped end abutting the hanger, and means for drawing the ends of the flange 30 toward the hanger for clamping the innerlapped end between the outerlapped end and the pressure bar. 35
6. A metallic flume including adjoining sections having overlapped ends, a transverse hanger adjacent to the edges of the overlapped ends, a pressure bar inside the innerlapped end abutting the hanger, and means drawing the outerlapped end toward 40 the hanger for clamping the innerlapped end between the outerlapped end and the pressure bar, there being outwardly extending tongues struck downward from the transverse hanger inside the ends of the pressure bar and wedged upward against the same to press them outward. 45

WILLIAM L. CALDWELL.
